SEWING MACHINE AND ATTACHMENT
THEREFOR

Raymond H. Van Wagener, Stamford, Conn., assignor to The Singer Manufacturing Company, Elizabeth, N. J., a corporation of New Jersey

Application December 27, 1950, Serial No. 202,828

14 Claims. (Cl. 112—101)

1

This invention relates to improvements in sewing machines and, more particularly, to a mechanism for periodically indenting an edge of the work being stitched, thereby to produce in the work a shell-edge effect, and at the same time laying a cord along the indented work edge so that the cord will be secured to the work by means of these stitches.

A primary object of this invention is to provide a sewing machine with a combined work-edge indenting and cord-laying mechanism which may be inexpensively manufactured and readily applied to existing type sewing machines.

With these and other objects in view, as will hereinafter appear, the invention comprises the devices, combinations and arrangements of parts described in connection with the accompanying drawings, which illustrate a preferred embodiment of the invention and in which:

Fig. 1 represents a front side elevation, partly in vertical longitudinal section, of a portion of a sewing machine containing the improved work-surfing and cord-laying mechanism.

Fig. 2 represents an enlarged fragmentary top plan view, partly in section, along the line 2—2 of Fig. 1.

Fig. 3 represents an enlarged fragmentary top plan view partly in section, along the line 3—3 of Fig. 1.

Fig. 4 represents a fragmentary sectional view taken substantially along the line 4—4 of Fig. 2.

Fig. 5 represents a detail view showing the presser-foot and feed-dog in side elevation and the throat-plate in section.

Fig. 6 represents a bottom plan view of the 35 presser-foot of the machine.

Fig. 7 represents a sectional view taken substantially along the line 7—7 of Fig. 2.

The present improvements have been embodied in a lock-stitch sewing machine of the class disclosed in the United States patent of F. W. Breul, No. 2,424,793, July 29, 1947. The sewing machine has a frame including a bed-plate 10, from one end of which rises a hollow standard 11 of a bracket-arm terminating in an overhanging head 12. Journaled for vertical reciprocation in the head 12 is a needle-bar 13 carrying at its lower end a needle 14. Also mounted in the head 12 is the usual spring biased presser-bar 15 carrying at its lower end portion a presser-foot 16.

The needle 14 operates through a suitably apertured throat-plate 17, secured upon and forming with the bed-plate 10 a work-support. Disposed below the throat-plate 17 and com-

plemental to the needle 14 in the formation of lock-stitches, is a rotary loop-taker 18 of the rotary hook type and having a thread-loop seizing beak 19. The rotary loop-taker 18 rotates twice for each needle reciprocation and casts the needle-thread-loops about a mass of under thread contained in a thread-case 20 journaled in the loop-taker and restrained against rotation therewith.

10 The loop-taker 18 is suitably secured upon one end of a horizontal loop-taker shaft 21, which is rotatably journaled in spaced bushings 22, 22. The bushings 22, 22 are suitably secured in a wall 23 depending from the bed-plate 10; said wall 23 forming a portion of a gear casing providing a lubricant chamber 24. At its end opposite the loop-taker 18, the loop-taker shaft 21 carries a spur gear 25 disposed within the lubricant chamber 24.

15 In mesh with the spur gear 25 are teeth 26 provided internally of a flange 27 of a driving gear wheel 28; said gear wheel 28 being disposed in the lubricant chamber 24 and adapted to dip into a supply of lubricant contained in said chamber. The driving gear wheel 28 is secured in a suitable manner upon one end of a horizontally disposed bed-shaft 29, which rotates once for each needle reciprocation. The bed-shaft 29 is journaled adjacent the gear 28 in a bearing-bushing 30 secured in another gear casing wall 31 depending from the bed-plate 10. Suitably secured upon the outboard end of the bed-shaft 29 is a peripherally grooved pulley 32 engaged by a driving belt 33 of the sewing machine in the usual manner.

20 The work is intermittently advanced across the work-support by a differential feeding mechanism including feed-dogs 34 and 35, both of which feed-dogs operate through suitable feed slots 36 provided in the throat-plate 17.

The feed-advance and -return movements are imparted to the feed-dogs 34 and 35 by means of suitable mechanism including a pair of eccentrics 37 and 38, while the feed lift movements are imparted to the feed-dogs by means of a third eccentric 39. The eccentrics 37 and 38 are disposed adjacent each other upon the bed-shaft 29 and are generally similar in construction to the feed-advance eccentric construction disclosed more fully in the United States patent of W. Myers, No. 2,128,031, August 23, 1938. The feed-lift eccentric 39 is also mounted upon the shaft 29 and thus, from the foregoing description, it will be understood that the four-motion feed movements are imparted to the feed-dogs

34 and 35 by the eccentrics 37, 38 and 39 through the medium of conventional mechanism which is not disclosed herein. By adjustment of the respective eccentrics 37 and 39, the feed-dogs 34 and 35 may be caused to have unison work-advancing movements, or either to full or stretch the work by imparting differential movements to the feed-dogs all in a manner as described in the above noted Breul Patent No. 2,424,793.

The flange 27 of the loop-taker driving gear wheel 23 is provided externally with spiral threads 40 to form a worm in driving engagement with the teeth of a worm wheel 41 which extends downwardly through an opening 42 in the bed-plate 10. This worm wheel 41 is suitably secured upon a cross-shaft 43 extending transversely of the bed-shaft 29 and disposed above the bed-plate 10. The cross-shaft 43 is suitably journaled in a generally rectangular housing bracket 44; the bracket 44 rising from the bed-plate 10 and being suitably secured thereon by screws 44'. The top portion of the bracket 44 is closed by a cover-plate 45 secured by screws as at 46.

Secured upon and for rotation with the cross-shaft 43, within the bracket 44 is an eccentric 47 embraced by a strap at one end of a pitman 48. At its other end, the pitman 48 is pivotally connected by a pivot bolt 49 to a crank-arm 50 journaled intermediate its ends upon a stub-shaft 51 which is suitably secured in the front and rear walls of the bracket 44. The lower end portion of the crank-arm 50 is pivotally secured, as by means of a bolt 52, to a connecting link 53 which, in turn, is pivotally connected by means of a pin 54 to an endwise reciprocating slide-bar 55. The slide-bar 55 is slidably mounted in an internal bracket lug 56 and an external bracket boss 57 for reciprocation transversely of the line of seam formation of the machine; said slide-bar 55 being disposed above the bed-plate 10 and substantially parallel to the bed-shaft 29.

For a more complete disclosure of the mechanism for reciprocating the slide-bar 55, reference may be had to the above noted Breul Patent No. 2,424,793.

In accordance with the present invention, the distal end portion of the slide-bar 55 is provided with a reduced shank 58 which is adapted to receive thereon a boss member 59 which is provided with a suitably shaped hole 60 for receiving the member 58. For locking the boss 59 upon the member 58, the boss is provided with a suitable set screw 61. Referring particularly to Figs. 2 and 3, the boss 59 is provided with a cylindrical aperture 62 in which is slidably mounted a cylindrical plunger 63. The forward end portion of the plunger 63 is provided with a lug 64 and by referring particularly to Figs. 3 and 4, it is to be understood that the lug 64, as well as its plunger 63, is provided with a vertically disposed slot 65 for receiving therein an edgewise vertically disposed work-edge indenting element or hem-deflecting blade 66. This blade is provided with an aperture 67 for receiving therein a screw 68 which is threaded directly into the lug 64 for locking the blade 66 in its proper position. By referring particularly to Fig. 4, it will be noted that the boss 59 is provided with a vertical slot 69 for receiving therein a rear finger portion 70 of the blade 66, which finger portion enters the slot 69 so as to prevent the plunger 63 and the blade 66 from turning within the aperture 62. In this connection, it will be noted from Fig. 4 that the boss 59 is provided at its under side with a flat face 71 which is disposed in substantial contact

with the throat-plate 17 thereby to prevent the slide-bar 55 from turning about its longitudinal axis. Still referring to Fig. 4, the lower forward edge portion 72 of the blade 66 is substantially in contact with the throat-plate 17 and the upper edge of the blade is downwardly inclined, as at 73, thereby to provide a narrow work-engaging edge.

The forward portion of the blade 66 is provided with a cord-guiding eye 74, the function of which will be hereinafter described in more detail. The rear end of the plunger 63 is provided with a central threaded aperture 75 which receives therein a threaded stud 76 having a head portion 77. For locking the head 77 in selective positions of adjustment relative to the plunger 63, there is provided on the stud 76 a threaded nut 78 which, when abutted against the end portion of the plunger 63, locks the stud within the plunger. Surrounding the plunger 63 and disposed between the boss 59 and the nut 78 is a coil spring 79 which functions to bias the plunger crosswise of the direction of seam formation and away from the stitching area.

The feed-dogs 34 and 35 are opposed by the bottom or sole-plate portion of the presser-foot 16 which is provided with a combined needle- and blade-clearance slot 80 which is disposed in alignment with the blade 66 and the needle 14. Formed within the sole-plate of the presser-foot is a work-clearance notch 81 which extends transversely of the presser-foot to communicate with the combined needle and blade notch or slot 80. This slot 81 divides the sole-plate into a forward work-engaging portion 82 and a rearward work-engaging portion 83. The sole-plate is pivotally attached to the presser-foot shank 84 by means of a conventional pivot pin 85 which is, in turn, secured to the lower end of the presser-bar 15 which is endwise movable in the bracket-arm head 12 and spring depressed in a conventional manner.

Disposed in front of the presser-foot 16 is a conventional scroll hemmer 86 having its shank 87 secured to the bed-plate 10 in a suitable manner. The delivery end of the hemmer 86 is located to direct the hem fold H, formed by the hemmer in the work W, under the sole-plate of the presser-foot in a conventional manner.

Suitably secured upon the bed-plate 10 at a location forwardly of the bracket 44 is an elongated arm 88 having a plurality of apertures 89, 89' therein which function as cord-guiding eyes for the purpose of directing a cord C from a source of supply to the stitching area in a manner as will hereinafter be described.

In the operation of the present machine, the slide-bar 55 and, consequently, the blade 66 perform one complete reciprocation during the formation of a plurality of stitches, as for example, six stitches. During its advancing movement, the blade 66 enters the presser-foot slot 80 and deflects the edge of the hem fold H inwardly sufficiently far to cause the needle 14 to descend outside the hem fold and thereby form a stitch extending over the edge of the work. The forward feed of the work, in conjunction with the action of the presser-foot 16, the return movement of the blade 66 and the resiliency of the material being stitched results in the needle again penetrating the work in its subsequent descent and until the hem fold is again deflected by the blade 66. Consequently, the stitched work presents a scalloped or shell edge.

appearance as illustrated in Fig. 2 of the drawings.

As noted hereinabove, the horizontal work-clearance notch 81 of the presser-foot is located intermediate the ends of the sole-plate, thus to divide the latter into a forward portion 82 and a rear portion 83. From Fig. 5 it may be seen that the forward and rear portions of the sole-plate have cooperating therewith the feed-dog 34 which is disposed beneath the presser-foot. Thus, the feed-dog is effective to feed the work beneath the presser-foot and away from the stitching area. In utilizing the present machine for both work-edge scalloping as well as for cord laying, a cord C is directed from a source of cord supply through one or more of the apertures 89 in the guide 88 and thereafter this cord is led through the cord-guiding means 74 of the blade 66 and then is directed beneath the presser-foot 16. The operation of the machine itself is substantially the same as hereinabove described with the blade 66 performing one complete reciprocation during the formation of a plurality of stitches, as for example six stitches. During its advancing movement, the blade 66 enters the presser-foot slot 80 and deflects the edge of the hem fold H inwardly sufficiently far to cause the needle 14 to descend outside the hem fold and at the same time the cord-guiding means positions the cord on the left-hand side of the needle so that the needle will descend on the outside of the cord thereby to form a stitch extending both over the edge of the work as well as over the cord so as to secure the cord to the edge portion of the work. Thereafter, the blade 66 withdraws from the work and the feeding mechanism advances the work which is stitched in the usual manner until the blade again functions to indent the work and present the cord to the stitching mechanism. Thus, the cord during the normal stitching operation will be laid alongside the scalloped edge of the work to produce work of the type which is illustrated in Fig. 2.

From the above it will be appreciated that the present cord-guiding means functions not only to present the cord to the work but, at the same time, it functions to lay the cord along the edge of the work. In order to perform these functions properly, the cord-guiding means must, on its backward movement, shift sufficiently far away from the presser-foot so as to gather a sufficient quantity of slack cord to enable the cord-guiding means to lay an optimum amount of cord about the scalloped edge, as above noted. In this connection, it is to be understood that a portion of the cord is disposed between the presser-foot 16 and the feed-dogs and whenever the feed-dogs function to feed the work away from the stitching area they, at the same time, function to draw the cord through the cord-guiding means. However, as the feeding operation continues, the blade 66 with its cord-guiding means withdraws from the stitching area and this action, of course, provides the cord-guiding means, between the latter element and the presser-foot, with a pre-determined length of slack cord, which amount depends upon the amplitude of backward movement of the cord-guiding means. In other words, the further the cord-guiding means moves away from the presser-foot the greater will be the amount of slack cord disposed between the cord-guiding means and the presser-foot, which cord is to be laid alongside of the successive scallops.

In order to insure that an optimum quantity of slack cord will be provided between the presser-

foot and the cord-guiding means, the present invention contemplates a provision of a cord-guiding means which will have an amplitude of movement which is not necessarily equal to the amplitude of movement of the slide-bar 55. Referring particularly to Figs. 2 and 3, it will be understood that as the slide-bar 55 reciprocates back and forth crosswise of the line of seam formation and toward and away from the presser-foot, the plunger head 77 will contact the forward portion of the external lug 57 on the withdrawal stroke of the slide-bar 55 and thus the rearward motion of the blade 66, together with that of the cord-guiding means, will be arrested to the end that the cord-guiding means will have a shorter amplitude of movement than the slide-bar 55. In other words, the plunger head 77 engages the stationary lug 57, whereby the boss 59 moves relatively to the plunger 63 during the continued retracting stroke of the slide-bar 55. By backing off the nut 78 from the end portion of the plunger 63, the stud 76 may be adjusted relative to the plunger 63 so that the head 77 may be shifted away from or toward the plunger 63. This adjustment will, of course, either lengthen or shorten the amplitude of movement of the blade 66, together with its cord-guiding means. From this, it will be appreciated that the present device may be so adjusted as to provide a proper amount of cord so that the machine may produce different types of scalloped and corded work.

Those skilled in the art will readily understand that the present boss 59, together with its plunger 63 and the work-indenting blade 66, as well as the cord-guiding means 74 are adapted to be applied to a sewing machine as a unitary device, and since the amplitude of movement of the blade 66 and its cord-guiding means may be adjusted, it will be clear that the present attachment may be applied to various machines irrespective of the throw of the slide-bar 55. Although the amplitude of movement of the plunger 63 may be varied, it is to be understood that the forward position which the blade 66 takes relative to the presser-foot is always the same for any one setting of the boss 59 upon the stem 58 of the slide-bar 55. In other words, even though the amplitude of backward movement of the plunger 63 is altered, the forward position which the blade 66 assumes relative to the presser-foot always remains the same. Thus, the present work-edge indenting and cord-laying mechanism comprises a substantially self-contained unit which may be readily applied to a standard type sewing machine without involving any great expense or undue effort.

Having thus set forth the nature of the invention, what I claim herein is:

1. In a sewing machine having stitch-forming and work-feeding mechanism, an endwise reciprocating member having a path of movement crosswise of the line of seam formation, means for reciprocating said member, a work-edge indenting and cord-guiding element carried by said member for movement with and relatively to said member, and stop-means limiting the retracting movement of said element during the continued retracting movement of said member.
2. In a sewing machine, the combination with stitch-forming mechanism, work-feeding mechanism, and driving means for actuating said stitch-forming and work-feeding mechanisms, of a work-indenting element and a cord-guiding element each mounted for reciprocation crosswise

of the line seam formation, means including a pair of members shiftable relative to each other in a straight line direction for operatively connecting said work-indenting and cord-guiding elements with said driving means, and means associated with one of said members for varying the amplitude of reciprocatory movement of said cord-guiding element.

3. In a sewing machine, the combination with stitch-forming mechanism including a presser-foot, work-feeding mechanism, and driving means for actuating said stitch-forming and work-feeding mechanisms, of a work-indenting element and a cord-guiding element each mounted for reciprocation toward and away from said presser-foot and crosswise of the line of seam formation, means including a pair of members shiftable relative to each other in a straight line direction for operatively connecting said driving means with said work-indenting and cord-guiding elements for reciprocating each of said elements crosswise of the line of seam formation, and to and from and entirely at one side of a predetermined line disposed adjacent said presser-foot and in parallelism with the line of seam formation, and means associated with one of said members for varying the amplitude of movement of said cord-guiding element to and from its associated predetermined line.

4. In a sewing machine, the combination with stitch-forming mechanism including a presser-foot, work-feeding mechanism, and driving means for actuating said stitch-forming and work-feeding mechanisms, of a work-indenting element mounted for reciprocation toward and away from said presser-foot and crosswise of the line of seam formation, cord-guiding means carried by said element, means including a pair of members shiftable relative to each other in a straight line direction for operatively connecting said driving means with said work-indenting element for reciprocating said element crosswise of the line of seam formation and to and from and entirely at one side of a predetermined line disposed adjacent said presser-foot and in parallelism with the line of seam formation, and means associated with one of said members for varying the amplitude of movement of said element to and from the predetermined line.

5. In a sewing machine, the combination with stitch-forming mechanism, work-feeding mechanism, and driving means for actuating said stitch-forming and work-feeding mechanisms, of a member mounted for reciprocation crosswise of the line of seam formation, said driving means being connected with said member for reciprocating the latter in timed relation with said stitch-forming and work-feeding mechanisms and through a predetermined amplitude, a work-edge indenting element carried by said member, cord-guiding means carried by said member, and means responsive to the movements of said member for periodically shifting said cord-guiding means relative to said member so as to cause said cord-guiding means to have an amplitude of movement relative to the line of seam formation substantially different from that of said member.

6. In a sewing machine, the combination with stitch-forming mechanism, work-feeding mechanism, and driving means for actuating said stitch-forming and work-feeding mechanisms, of a member mounted for reciprocation crosswise of the line of seam formation, said driving means being connected with said member for reciproc-

cating the latter in timed relation with said stitch-forming and work-feeding mechanisms and through a predetermined amplitude, a work-edge indenting element carried by said member, cord-guiding means carried by said member, means responsive to the movements of said member for periodically shifting said cord-guiding means relative to said member so as to cause said cord-guiding means to have an amplitude of movement relative to the line of seam formation substantially different from that of said member, and means for varying the amplitude of movement of said cord-guiding means relative to the line of seam formation.

7. In a sewing machine, the combination with stitch-forming mechanism, work-feeding mechanism, and driving means for actuating said stitch-forming and work-feeding mechanisms, of a member mounted for reciprocation crosswise of the line of seam formation, said driving means being connected with said member for reciprocating the latter in timed relation with said stitch-forming and work-feeding mechanisms and through a predetermined amplitude, a work-edge indenting element carried by and mounted for movement lengthwise of said member, cord-guiding means carried by said element, and means responsive to the movements of said member for periodically shifting said element lengthwise of said member.

8. In a sewing machine, the combination with stitch-forming mechanism, work-feeding mechanism, and driving means for actuating said stitch-forming and work-feeding mechanisms, of a member mounted for reciprocation crosswise of the line of seam formation, said driving means being connected with said member for reciprocating the latter in timed relation with said stitch-forming and work-feeding mechanisms and through a predetermined amplitude, a work-edge indenting element carried by and mounted for movements lengthwise of said member, spring means associated with said element for biasing said element away from the line of seam formation, cord-guiding means carried by said element, and means responsive to the movements of said member for periodically shifting said element lengthwise of said member and in a direction in opposition to the action of said spring means.

9. In a sewing machine, the combination with a frame, stitch-forming mechanism, work-feeding mechanism, and driving means for actuating said stitch-forming and work-feeding mechanisms, of a member mounted upon said frame for reciprocation crosswise of the line of seam formation, said driving means being connected to said member for reciprocating the latter in timed relation with said stitch-forming and work-feeding mechanisms and through a predetermined amplitude, a work-edge indenting element carried by and mounted for movements lengthwise of said member, spring means associated with said element for biasing said element away from the line of seam formation, cord-guiding means carried by said element, and means carried by said frame and disposed adjacent said member for periodically shifting said element relative to said member and against the action of said spring means in response to the movements of said member.

10. In a sewing machine having a frame, stitch-forming mechanism, work-feeding mechanism, driving means for actuating said stitch-forming and work-feeding mechanisms, and a member mounted for reciprocation crosswise of

the line of seam formation, said driving means being connected to said member for reciprocating the latter in timed relation with said stitch-forming and work-feeding mechanisms and through a predetermined amplitude; the improvement which consists in the provision of a combined work-edge indenting and cord-laying device, said device comprising a boss removably mounted upon said member, a work-edge indenting element carried by and mounted for movement relative to said boss, cord-guiding means carried by said element, and means secured to said element for periodically engaging said frame in response to the movements of said member thereby periodically to shift said element relative to said boss and said member.

11. In a sewing machine having a frame, stitch-forming mechanism, work-feeding mechanism, driving means for actuating said stitch-forming and work-feeding mechanisms, and a member mounted for reciprocation crosswise of the line of seam formation, said driving means being connected to said member for reciprocating the latter in timed relation with said stitch-forming and work-feeding mechanisms and through a predetermined amplitude; the improvement which consists in the provision of a combined work-edge indenting and cord-laying device, said device comprising a boss removably mounted upon said member, a work-edge indenting element carried by and mounted for movement relative to said boss, cord-guiding means carried by said element, spring means for biasing said element in one direction, and means secured to said element for periodically engaging said frame in response to the movement of said member thereby periodically to shift said element relative to said boss and said member and in opposition to the action of said spring means.

12. In a sewing machine having a frame, stitch-forming mechanism, work-feeding mechanism, driving means for actuating said stitch-forming and work-feeding mechanisms, and a member mounted for reciprocation crosswise of the line of seam formation, said driving means being connected to said member for reciprocating the latter in timed relation with said stitch-forming and work-feeding mechanisms and

through a predetermined amplitude; the improvement which consists in the provision of a combined work-edge indenting and cord-laying device, said device comprising a boss removably mounted upon said member, a plunger slidably mounted within said boss, a work-edge indenting element carried by one end of said plunger, cord-guiding means carried by said element, spring means for biasing said plunger lengthwise of itself and away from said stitch-forming mechanism, and means provided on the other end of said plunger for periodically engaging said frame in response to the movement of said member thereby periodically to shift said plunger relative to said boss and in opposition to the action of said spring.

13. A work-indenting attachment for sewing machines, comprising, a boss adapted to be reciprocated back and forth crosswise of the line of sewing machine seam formation, a work-indenting blade slidably mounted upon said boss, spring means for biasing said blade toward one end of said boss, and means connected with said blade for limiting the movement of said blade relative to said boss.

14. A work-indenting attachment for sewing machines, comprising, an apertured boss adapted to be reciprocated back and forth crosswise of the line of sewing machine seam formation, a plunger slidably mounted within said boss, a work-indenting blade mounted upon one end portion of said plunger, a spring associated with said plunger for biasing said blade toward said boss, and a head member carried upon the other end of said plunger for engagement with the sewing machine thereby to produce a differential movement between said boss and said plunger in response to the movements of said boss.
